CLAIM

The ornamental design for a wristband containing a wireless electronic fob for a marine vessel, as shown and described.

DESCRIPTION

FIG. 1 is a perspective view of a wristband containing a wireless electronic fob for a marine vessel.

FIG. 2 is a top view thereof.

FIG. 3 is a bottom view thereof.

FIG. 4 is a side view thereof.

FIG. 5 is an opposite side view thereof.

FIG. 6 is an end view thereof; and,

FIG. 7 is an opposite end view thereof.

The dot-dash broken lines define the boundary of the claim, which extends to the boundary but does not include the boundary, while all other broken lines depict portions of the wristband containing the wireless electronic fob for a marine vessel that form no part of the claimed design.
